UNITED STATES PATENT OFFICE.

EDWARD ALBERT FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A CHAFING-DISH HANDLE.

42,502.

Specification for Design.

Patented May 14, 1912.

Application filed December 26, 1911. Serial No. 668,001. Term of patent 7 years.

To all whom it may concern:

Be it known that I, EDWARD A. FARR, a citizen of the United States, residing at Meriden, New Haven county, Connecticut, have invented a new, original, and ornamental Design for a Chafing-Dish Handle, of which the following is a specification, reference being had to the accompanying drawings, forming a part thereof, in which—

Figure 1 is a plan view of the handle, to-

gether with its bracket. Fig. 2 is a side elevation thereof.

I claim:

The ornamental design for a chafing dish handle as shown.

EDWARD ALBERT FARR.
